UNITED STATES PATENT OFFICE.

LEWIS S. BARBER, OF GREENSBORO, NORTH CAROLINA, ASSIGNOR OF ONE-HALF TO JOHN P. JOHNSON, OF GREENSBORO, NORTH CAROLINA.

SAFETY ATTACHMENT FOR CAR-BRAKES.

SPECIFICATION forming part of Letters Patent No. 728,654, dated May 19, 1903.

Application filed February 5, 1903. Serial No. 142,048. (No model.)

To all whom it may concern:

Be it known that I, LEWIS S. BARBER, a citizen of the United States, residing at Greensboro, in the county of Guilford and State of North Carolina, have invented a new and useful Safety Attachment for Car-Brakes, of which the following is a specification.

My invention relates to automatic means for applying the air-brakes of railroad-cars upon the car-wheels leaving the track; and it consists in the various features hereinafter described and claimed.

In the accompanying drawings, Figure 1 is a vertical transverse section of a car-truck to which is applied one embodiment of my invention. Fig. 2 is a vertical longitudinal section therethrough, and Fig. 3 is an enlarged sectional detail of the lever.

Similar characters indicate like parts throughout the several figures of the drawings.

Some usual form of car-truck is designated by the letter T, it having the bolster *b*, axles *a a*, and pairs of wheels *w w*. Just inside each pair of wheels is a horizontal stay 10, curved at its ends 11 to partly encircle the axle and having depending projections 12 from said ends. It is supported at its center from the bolster by pairs of loops or hangers 13 13, through which it passes. The hangers may be secured together to hold the stay fast by bolts 14, passing through openings at or near the bottom of each, and the curved ends of the stay are shown as braced by inclined bars 15, bolted to them.

Pivoted by a bolt 16 upon each stay projection 12 is a lever 17 of suitable form, with its lower end in proximity with the wheel and a less distance from the top of the rail than said top is from the cross-ties. This lever at its upper extremity carries a disk 18, preferably of rubber or like elastic material, which coacts with and closes an opening in an elastic ring or gasket 19, mounted upon the end of a transverse pipe 20, which constitutes an extension from and is joined to the train-pipe 20 of the air-brake system by a preferably

flexible pipe 21. The pipe 20 is conveniently carried by the opposite stay projection 12, the flexibility of the pipe 21 permitting the free movement of the truck without danger of breaking the piping. The coacting elastic elements furnish a valve and form a connector between the lever and air-brake system. The opposite end of the pipe 20 may 55 coact with the lever adjacent to the opposite wheel in the same manner.

It will be seen that should the car or truck leave the rail one of the levers upon the side at which the wheel takes the outer side will 60 at once contact with the rail or other relatively fixed object, this, as a result of the location of the lever, occurring before the wheel strikes the road-bed. By this contact it will be swung rearwardly about its pivot to the 65 position shown in dotted lines in Fig. 2, carrying its upper end off the end of the pipe 20, admitting air to the system, and by the consequent destroying of the vacuum in the train-pipe applying the brakes of the entire train. 70 This will bring it to a stop and will prevent the leaving of the road-bed proper and the occurrence of such accidents as the cars going over embankments.

Having thus described my invention, I 75 claim—

1. The combination with a car-truck and the train-pipe of an air-brake system having an opening to the external air, of a lever movable by contact with a relatively fixed object 80 when the wheel leaves the track, and an elastic member carried by the lever and normally closing the opening in the air-brake system.

2. The combination with a car-truck and the train-pipe of an air-brake system, of a 85 support carried by the truck, an extension from the train-pipe mounted on the support, and a lever pivoted to swing upon the support and adapted to coact with the train-pipe extension to open it when the train leaves the 90 track.

3. The combination with a car-truck and the train-pipe of an air-brake system, of stays supported from the central portion of the

truck at each side, extending in proximity to the axles and provided with a projection below the axle and near each wheel, a transverse extension from the train-pipe carried by the stays, and a lever pivoted to each support and coacting with the train-pipe extension.

In testimony that I claim the foregoing as my own I have hereto affixed my signature in the presence of two witnesses.

LEWIS S. BARRER.
